UNITED STATES PATENT OFFICE.

WILLIAM G. LINDEMANN, OF MILWAUKEE, WISCONSIN.

SOCKET FOR ELECTRIC LAMPS.

No. 926,754.

Specification of Letters Patent.

Patented July 6, 1909.

Application filed February 20, 1909. Serial No. 479,149.

To all whom it may concern:

Be it known that I, WILLIAM G. LINDEMANN, a citizen of the United States, residing at Milwaukee, in the county of Milwaukee and State of Wisconsin, have invented a new and useful Socket for Electric Lamps, of which the following is a specification.

My invention relates to improvements in lamp sockets for electric lamps, and pertains especially to that class of sockets employed in what are known as husk chandeliers.

The object of my invention is to provide a form of construction in which the lamp and cord plug may be removed without disengaging the shade, the casing being integrally formed or struck up from a single piece of metal.

My invention also has for its object certain structural improvements hereinafter more particularly described and claimed.

In the following description, reference is had to the accompanying drawings, in which—

Figure 1 is an elevation of my improved lamp socket with the lamp in position. Fig. 2 is a vertical sectional view of the socket and plug. Fig. 3 is a view of the same as seen from the upper side. Fig. 4 is a detail of the screw threaded insulated bushing.

Like parts are identified by the same reference characters throughout the several views.

The casing A is integrally formed or pressed from a single piece of sheet metal and provided with a thimble B, which receives the insulated cap nut C, through which the cords D pass. The body of the casing A is preferably in the form of an inverted cup with an annular bead a near the lower margin or open end, and below this bead the marginal portion of the casing is pressed or creased to form screw threads a'. These threads being formed by pressing or creasing the sheet metal composing the casing, it is obvious that both the interior and exterior surface is threaded. A shade holder E, preferably also formed of sheet metal, is provided with a threaded portion e, which engages the exterior surface of the screw threads a' on the casing A. This shade holder is provided with ordinary set screws E' for engaging and holding the shade. A switch bracket F containing the ordinary snap switch G is mounted between the insulating disks H, H' and the switch stem I

is connected with a key J by means of a screw K connected with the key and extending through an aperture in the casing A into a screw threaded socket in the stem I. 60

The parts G, H, H', J, I, and K may all be of any ordinary construction, except that the upper insulating disk H is provided with notches L on opposite sides thereof, the casing A being provided with stud pins N adapted to enter these notches and hold the switch frame in position with the stem I registering with an aperture K' in the casing A, whereby the key J may be readily attached or removed.

O is a non-conducting lining for the casing A and the key J is provided with a non-conducting annulus P, which enters the aperture K' in the casing and prevents any metallic contact between the screw K and the wall of the casing A. The switch frame is 70 provided with an ordinary cup-shaped screw threaded member Q, which constitutes the socket proper into which the lamp is screwed, but between this member Q and the lower margin of the casing A, I have provided a removable bushing R composed of insulating material and having its exterior surface threaded to engage the screw threads a' within the casing A. This bushing extends upwardly beyond the bead a and engages the 80 under surface of the disk H', thus supporting the switch frame and socket member Q independently of the key and screw K.

With this construction, it is obvious that the switch frame and socket member Q may 90 be readily removed by unscrewing the key J and bushing R without disturbing the shade. On replacing the switch frame, the studs N compel an adjustment of the frame in the proper position to permit screw K to reenter 95 the socket in the end of the switch stem I. The shell being in one piece, it is obvious that there is no danger that any of the parts will become accidentally disconnected. The bead a serves as a stop for the shade holder E, 100 which not only limits the upward movement of this holder, when it is being screwed into place, but also causes the shade holder to bind upon the screw threads and locks it in position. 105

Having thus described my invention, what I claim as new, and desire to secure by Letters Patent is—

1. In a device of the described class, the combination with a switch frame and lamp socket, of an integrally formed casing having an open lower end portion creased to form

internal and external screw threads, a shade holder exteriorly engaging said threads and a non-conducting bushing interiorly engaging said threads and supporting the switch mechanism.

2. In a device of the described class, the combination with the switch mechanism, of an integrally formed casing adapted to receive said mechanism and provided at its 10 lower end with means for supporting a shade holder from its exterior surface and the switch mechanism from its interior surface.

3. In a device of the described class, the combination with the switch mechanism, of 15 an integrally formed casing adapted to receive said mechanism and provided at its lower end with means for supporting a shade

holder from its exterior surface and the switch mechanism from its interior surface, 20 said casing near its upper end being provided with inwardly projecting studs adapted to engage the switch mechanism in but one position of adjustment, said casing being provided with an aperture adapted to register 25 with the switch actuating devices when in such position of adjustment, and adapted to receive a switch actuating key.

In testimony whereof I affix my signature in the presence of two witnesses.

WILLIAM G. LINDEMANN.
